SPARK AMPLIFIER FOR USE IN THE IGNITION SYSTEMS OF INTERNAL COMBUSTION ENGINES

Application filed June 20, 1932. Serial No. 618,398.

The object which I have in view is the improvement of the efficiency of the spark plugs which are employed to ignite the fuel charges in the engine cylinders, by building up the 5 voltage of the current delivered by the secondary circuit of the ignition system through the distributor to the spark plug.

For the accomplishment of this object I interpose my improved amplifier in the lead 10 conductor connecting the distributor to the induction coil, and thus obtain a spark able to jump a wider gap and therefore more intense, thus greatly improving the ignition of the fuel charges.

The desirability of such improvement is well recognized in the automotive art, and my improved amplifier fully satisfies the requirements by producing more power and mileage from a given quantity of fuel and 15 also providing for quick starting and rapid power development.

In the accompanying drawing, wherein I have illustrated a practical embodiment of the principles of my invention, Fig. 1 is an 20 enlarged view in longitudinal section showing one form of my amplifier.

Fig. 2 is a plan view of one of the annular dielectric or insulating disks used therein.

Fig. 3 is a plan view of one of the annular 25 electrodes used therein.

Fig. 4 is a view similar to Fig. 1 but showing a modified structure.

Fig. 5 is a plan view of one of the dielectric disks used therein.

Fig. 6 is a like view of one of the annular electrodes.

Fig. 7 is a like view of one of the dielectric guard rings used therein.

Fig. 8 is an elevation showing my amplifier interposed between the secondary lead 30 and the distributor of an ignition system.

Referring first to Figs. 1, 2 and 3 of the drawing, 1 represents a cylindrical sleeve formed of fibre, hard rubber or other suitable insulating material. The sleeve is internally threaded from one end, the thread ending to form an internal shoulder 2 adjacent the other end of the sleeve.

3 represents a plug of conductive metal, 35 such as brass, of proper diameter and exter-

nally threaded to screw down into the sleeve 1 until it abuts against the shoulder 2.

The plug 3 is cup-shaped, its cavity 4 facing the entrance end of the sleeve.

5 represents a second plug also of conductive metal and externally threaded so as to be screwed into the entrance end of the sleeve.

6 represents a plurality of annular disks which form the electrodes. Such disks are formed of polished steel and the material may 40 conveniently be chrome or "stainless" steel.

The disks are of proper external diameter to loosely fit the bore of the sleeve 1.

7 represents annular disks of dielectric material, such as mica, said disks having substantially the same size of bore or central opening as have the electrodes 6 but having a 45 less external diameter.

The electrodes 6 and the dielectric disks 7 are disposed in alternate arrangement in the sleeve 1 between the plugs 3 and 5, the electrodes being positioned against the inner ends of the plugs, and the plug 5 being screwed in until the parts are tightly clamped together 50 and in proper position.

The plug 5 is provided with an axial socket 8 opening outwardly to receive the end of the conductor 9 which is connected to the secondary of the usual inductive coil. The socket 55 extends deeply into the plug leaving but a relatively thin floor.

10 represents a screw of brass or other conductive material which is screwed outwardly through a threaded hole in the center of the 60 plug 3. The screw is permanently fixed relative to the plug, as by solder, as illustrated at 11.

12 represents an expansion nut comprising a sleeve having its outer end closed. The 65 sleeve has a differential bore, the larger bore loosely surrounding the screw 10 while the smaller bore which is adjacent the closed end of the nut is threaded to receive the screw. The nut is split radially from its closed end 70 as illustrated at 13 so that it will expand as it is tightened up on the screw.

The nut 12 is inserted in the usual socket 14 in the center of the distributor 15 and then 75 expanded.

The preferred installation of the amplifier is clearly shown in Fig. 8.

In the modification illustrated in Figs. 4 to 7, inclusive, the disk electrodes 6a are of less external diameter than the dielectric disks 7a, and when the disks are assembled the dielectric rings 7b surround the disks 6a, and thus arcing or current travel between the outer perimetral edges of adjacent electrodes 10 is prevented and the break down or arcing between the electrodes is confined to the inner circular edges of the latter.

It will be noted that the amplifier is provided with a continuous open passage between 15 the plugs and formed by the central openings of the electrodes and dielectric disks.

Thus the spark discharge will jump from electrode to electrode without hindrance such as would occur were the passage more or less 20 obstructed by dielectric or insulating material. Thus, for instance, were the annular disks strung or supported on an insulating member, there would be a tendency for the spark to carbonize the surface of the insulator 25 and thereby establishing a low resistance path between the electrodes which would thus negative the function of the device.

Again, the interior spaces of the amplifier are practically air-tight and thus ionization 30 of the trapped gas will occur which will lower the resistance for the discharge.

Moreover the provision of the internal free space provides for cooling the electrodes after or between spark discharges by absorbing the 35 radiant heat energy from the electrodes and distributing it to the cooler portions of the chamber, and thence the heat is carried away by conduction through the plugs to atmosphere.

40 The cup of the lower plug greatly enlarges this chamber and thus enhances this cooling action.

In the modification illustrated in Figs. 4 to 7, inclusive, the total spark discharge occurs 45 between the inner annular surfaces of the electrodes as the path is blocked adjacent the wall of the sleeve by the interposition of dielectric material. Thus no carbonization can occur between the electrodes at their outer perimetral surfaces.

The insertion of the end of the lead conductor, which is ordinarily provided with the usual brass terminal, deeply into the plug 5 provides a means for conducting the heat 55 energy from the plug and thus aids in cooling the amplifier.

The mounting of the amplifier directly on the distributor by means of the expansion nut provides the convenient installation of 60 my amplifier in the ignition system of any standard internal combustion engine without requiring any alteration thereof. The end of the lead conductor is simply unstepped from the distributor and inserted in the 65 socket 8 of the amplifier and the amplifier is

mounted in place by the insertion of the expansion nut in the socket 14 of the distributor and its expansion to tighten it in place.

My device is simple and inexpensive to manufacture and thus may be sold at low 70 cost. It is durable and comprises no parts likely to become foul or broken.

I claim:

1. In a spark-amplifier for internal combustion engines, the combination of a cylindrical sleeve formed of insulating material and internally threaded, a pair of connector plugs formed of conductive material and screwed into said sleeve, and a plurality of annular electrodes and of annular dielectrics 75 arranged in alternate relation in said sleeve and between the inner ends of said plugs, said electrodes and dielectrics being fixed in proper relation by screwing up one of said plugs, whereby the central openings of said electrodes and dielectrics form a continuous 80 inclosed chamber extending between said plugs.

2. In a spark-amplifier for internal combustion engines, the combination of a cylindrical sleeve formed of insulating material and internally threaded, a pair of connector plugs formed of conductive material and screwed into said sleeve, and a plurality of annular electrodes and of annular dielectrics 85 arranged in alternate relation in said sleeve and between the inner ends of said plugs, an electrode being in surface contact with the inner end of each of said plugs, said electrodes and dielectrics being fixed in proper relation by screwing up one of said plugs, whereby the central openings of said electrodes and dielectrics form a continuous 90 inclosed chamber extending between said plugs.

3. In a spark-amplifier for internal combustion engines, the combination of a cylindrical sleeve formed of insulating material and internally threaded, a pair of connector plugs formed of conductive material and screwed into said sleeve, one of said plugs being cup-shaped with its cavity at its inner 95 end, and a plurality of annular electrodes and of annular dielectrics arranged in alternate relation in said sleeve and between the inner ends of said plugs, said electrodes and dielectrics being fixed in proper relation by screwing up one of said plugs, whereby the central openings of said electrodes and dielectrics form a continuous 100 inclosed chamber extending between said plugs.

4. In a spark-amplifier for internal combustion engines, the combination of a cylindrical sleeve formed of insulating material and internally threaded, a pair of connector plugs formed of conductive material and screwed into said sleeve, a plurality of annular electrodes and of annular dielectrics 110 arranged in alternate relation in said sleeve and between the inner ends of said plugs, said electrodes and dielectrics being fixed in proper relation by screwing up one of said plugs, whereby the central openings of said electrodes and dielectrics and the cavity of said plug form a continuous 115 inclosed chamber within said sleeve.

5. In a spark-amplifier for internal combustion engines, the combination of a cylindrical sleeve formed of insulating material and internally threaded, a pair of connector plugs formed of conductive material and screwed into said sleeve, a plurality of annular electrodes and of annular dielectrics arranged in alternate relation in said sleeve and between the inner ends of said plugs, said electrodes and dielectrics being fixed in prop- 120

- er relation by screwing up one of said plugs, whereby the central openings of said electrodes and dielectrics form a continuous inclosed chamber extending between said plugs, and means for preventing arcing between the electrodes adjacent the wall of the sleeve.
5. In a spark-amplifier for internal combustion engines, the combination of a cylindrical sleeve formed of insulating material and internally threaded, a pair of connector plugs formed of conductive material and screwed into said sleeve, a plurality of annular electrodes and annular dielectrics arranged in alternate relation and held in place between the inner ends of the plugs, the central openings of said electrodes and dielectrics forming a continuous inclosed chamber between the plugs, and a socket formed in one of said plugs to receive the end of a lead conductor.
6. In a spark-amplifier for internal combustion engines, the combination of a cylindrical sleeve formed of insulating material and internally threaded, a pair of connector plugs formed of conductive material and screwed into said sleeve, a plurality of annular electrodes and annular dielectrics arranged in alternate relation and held in place between the inner ends of the plugs, the central openings of said electrodes and dielectrics forming a continuous inclosed chamber between the plugs, and a socket formed in one of said plugs to receive the end of a lead conductor, the floor of said socket being relatively thin to facilitate the conduction of heat from the amplifier.
7. In a spark-amplifier for internal combustion engines, the combination of a cylindrical sleeve formed of insulating material and internally threaded, a pair of connector plugs formed of conductive material and screwed into said sleeve, a plurality of annular electrodes and annular dielectrics arranged in alternate relation and held in place between the inner ends of the plugs, the central openings of said electrodes and dielectrics forming a continuous inclosed chamber between the plugs, a screw extending outwardly from one of said plugs and an expansion nut mounted on said screw and adapted to be inserted in the socket connection of a distributor and the like.
8. In a spark-amplifier for internal combustion engines, the combination of a cylindrical sleeve formed of insulating material and internally threaded, a pair of connector plugs formed of conductive material and screwed into said sleeve, and a plurality of annular electrodes and annular dielectrics arranged in alternate relation and held in place between the inner ends of the plugs, the central openings of the electrodes and dielectrics forming a continuous inclosed chamber between the plugs, the internal diameters of the electrodes being less than those of the dielectrics whereby to facilitate spark-discharge between the inner annular surfaces of the electrodes.
9. In a spark-amplifier for internal combustion engines, the combination of a cylindrical sleeve formed of insulating material and internally threaded, a pair of connector plugs formed of conductive material and screwed into said sleeve, a plurality of annular electrodes and annular dielectrics arranged in alternate relation and held in place between the inner ends of the plugs, the central openings of the electrodes and dielectrics forming a continuous inclosed chamber between the plugs, the internal diameters of the electrodes being less than those of the dielectrics whereby to facilitate spark-discharge between the inner annular surfaces of the electrodes, and means for preventing spark-discharge between the outer annular surfaces of the electrodes.
